Primary Examiner — Susan Bennett Hattan*Assistant Examiner* — Janice Hallmark(74) *Attorney, Agent, or Firm* — Locke Lord LLP; Tim Tingkang Xia, Esq.(57) **CLAIM**

The ornamental design for an electronic cigarette atomizer, as shown and described.

DESCRIPTION

FIG. 1 is a front elevation view of an electronic cigarette atomizer;

FIG. 2 is a left side elevation view of the electronic cigarette atomizer;

FIG. 3 is a top plan view of the electronic cigarette atomizer;

FIG. 4 is a bottom plan view of the electronic cigarette atomizer;

FIG. 5 is a first perspective view of the electronic cigarette atomizer; and,

FIG. 6 is a second perspective view of the electronic cigarette atomizer.

The broken lines in FIGS. 1 through 6 depict parts of the electronic cigarette atomizer that form no part of the claimed design.
